MINE

Wesley N. Ensign, Jr., Babylon, N. Y.

Application December 19, 1944, Serial No. 568,905

1 Claim. (Cl. 102—8)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to mines.

A purpose of the invention is to provide a device which, when used in conjunction with or as a part of an explosive mine, will make removal of the mine more difficult by causing it to explode if the mine is tilted or moved.

Another purpose is to provide a tamper proof mine that can be disarmed only by those having the combination number applicable to the mine.

Other purposes will become apparent from the following description.

Reference is now had to the drawings, in which similar reference characters refer to similar parts throughout the several figures and in which:

Figure 1 is a diagrammatic partly cutaway view of a land mine casing showing one form of the tamper proof device, including combination adjusting switch.

Figure 2 shows a diagrammatic partly cutaway view of a land mine casing showing another form of the tamper proof device, including pull adjusting switch.

Figure 3 is a partly diagrammatic and partly sectional view of a marine mine casing showing the combination adjusting switch and mercury contact switch.

Figure 4 is a view of a portion of the mine casing of Figure 1 as seen from the outside, showing the binding posts and external combination knobs and graduations, and

Figure 5 is a plan view of the top of the pendulum switch.

In connection with the use of mines, whether of the land or marine type, it is desirable to prevent the removal of the mine until it has either been exploded by contact with an enemy land or sea vehicle, or has served to prevent the enemy from traversing the area covered by the mine field. This invention shows a means by which removal of mines is rendered quite difficult.

In Figure 1 the tamper-proof device is shown inside a land mine 1 of the pressure type which is designed to explode when sufficient pressure is exerted upon the pressure receiver 2. The rest of the usual internal structure of the pressure type mine is not shown in the drawing. Within the mine body a pendulum 3 is suspended in a chamber 4, the pendulum being suspended through an aperture 5 in the platform 6 from a bead 7 which is fastened to or made integral

with the pendulum shaft 18. The platform 6 and the sides of the chamber 4 are preferably made of material which does not conduct electricity so that elements mounted on or touching it need not have individual insulators. The pendulum is provided with a spherical weight 8 at its lower end and a metal contact disk 9 at its upper end. A metal contact ring 10 is positioned as indicated, concentric and coplanar with contact disk 9.

5 The contact ring 10 bears a number of metal contact points 24 spaced around its inner surface with points projecting inward toward the contact disk 9. The distance separating the contact disk 9 from the contact points 24 is small

10 so only a little movement is needed to bring them together. When the pendulum is centered, none of the contact points 24 of the contact ring 10 are in contact with the contact disk 9. The contact disk 9 of the pendulum 3 is connected by pigtail 17 and wire c to one terminal of an electric battery 19 and the other terminal of the battery is connected by the wire d to one terminal of an electric detonator or primer 20. The contact ring 10 is connected by wire a to contact arms

15 11, 12 and 13, each of which is adapted to be turned so as to be connected with its own contacts A, B, C or D. Thus, contact arm 11 can be turned to connect with either contact A, B, C or D, as shown in the drawing. Similarly

20 contact arm 12 has its own set of 4 contacts, and so has contact arm 13. It will be seen in the diagram that all the contact arms are connected together and to wire a. Likewise, all the contact points except one in each group of four, are connected together and to wire e, as shown. The

25 contacts which are connected to wire e will be designated as live contacts while those which, like contact B of contact group 16, or contacts A and B of contact groups 15 and 14 respectively, are not connected to anything, will be designated as dead contacts. Thus, if any contact arm is

30 connected to any live contact, then there is a continuous electrical connection from the contact ring 10 through wire a, through a contact arm and the live contact, through wire e to one terminal of the detonator 20. From the other terminal of the detonator, there is a continuous

35 electrical connection through wire d, through battery 19, and through wire c and pigtail 17 to the metal contact disk 9. If contact disk 9 is brought into contact with any contact on contact ring 10, by tilting the mine causing the pen-

40 dulum to tilt, then the electrical circuit is completed, permitting current to flow through the primer 20, exploding it and the mine.

45 It is apparent thus that if each contact arm

50

55

It is apparent thus that if each contact arm

is on a dead contact the electrical connection will not be continuous from the contact ring 10 to the electric detonator through wires *a* and *e*. Thus, even if the pendulum is tilted to bring the contact disk 9 into contact with the contact points 24 no current will flow through the primer 20 and hence it will not explode the mine. It follows that the tamper proof device is in the "safe" position when all contact arms are on dead contacts. The "safe" positions may be denoted by a combination showing the numbers of the dead contacts. For example the "safe" combination in Figure 1 would be BAB. The "safe" combination for each mine could be stamped or printed upon the surface of the mine in some code that would be known only to those who set the mines and remove them. Thus friendly personnel would be able to disarm the tamper proof device before removing or moving the mines.

While the anti-tamper device is in the safe position, the mine will not explode by merely tilting it, but the mine cannot be installed and set until the pendulum is centered so the contact disk 9 is not in contact with the contacts 24 on contact ring 10. To determine when these two members are out of contact two external binding posts 21 and 22 are mounted on the mine and insulated therefrom. These are connected respectively to one side of the detonator 20 and to the contact ring 10 as shown, and a voltmeter 23 is connected across the binding posts, having a voltage range suitable for measuring voltage of battery 19. Starting with the tamper proof device in the safe position, the mine is then leveled until the voltmeter 23 shows a zero voltage reading. This indicates that contact disk 9 is not in contact with any of contacts 24. It is then known that the mine is level and the contact arms 11, 12, and 13 can safely be turned to live contacts. It is then ready to explode if tilted out of level. The voltmeter 23 may be a portable one and one meter used for all the mines to be laid by the mine laying squad.

Figure 2 shows a modified form of the device of Figure 1, in which the pendulum switch is retained but the combination adjusting switch is omitted, and another arrangement substituted therefor. In the drawing, the wire *f* leads from the contact ring of the pendulum switch to one terminal of the battery 19 and the other battery terminal connects by means of wire *g* to one terminal of electric detonator 20. The other terminal of the detonator 20 connects by wire *i* to one terminal of a spring jack 30 mounted on the side wall of the pendulum chamber 4, said jack having two metal spring contactors 25 and 26 disposed side by side and making contact with each other by spring action. The other spring contactor 26 has its fixed base connected by wire *j* to the pigtail 17 and thence to the contact disk 9. A plug 27 having a non-conducting upper layer 29 and a conducting metal lower layer 28 is adapted to be inserted between the prongs 25 and 26 of the jack 30 and thus to separate them when inserted. The conducting lower portion 28 of the plug 27 makes contact with the prong 26 of the jack 30 when inserted therein, and a wire *k* is connected to said conducting portion. The other end of wire *k* leads through a baffle 56 and an aperture 31 in the mine casing and thence to the outside of the mine where it is connected to one terminal of a voltmeter 23 of a range suitable to measure the voltage of battery 19. The other terminal of the voltmeter 23 is connected by wire *m* to a binding post 32 mounted on the

outside of the mine casing and said binding post is connected by wire *h* to the wire *g* which connects the battery 19 and the detonator 20 together as already described. A pull cord 33 is tied to any portion of wire *k* external to the mine, and a pull ring 34 is attached to the free end of said cord 33. It is apparent that when the plug 27 is inserted in the jack 30, a pull on the pull ring 34 will pull the plug out of the jack.

The mine may be shipped and stored with the plug 27 inserted in the jack 30 thus keeping the prongs 25 and 26 from making electrical contact with each other, although the conducting portion 28 of the plug makes contact with the prong 26 of the jack. The external end of wire *k* may be insulated and left attached by adhesive tape to the outside surface of the mine together with the ring 34. The meter 23 may be packed separately for safety from rough handling and may be used by the mine laying detail for setting a number of mines since it is only used for setting the mines. When the mine is to be set in a mine field, it is placed in position and then the voltmeter 23 is connected to the binding post 32 and the wire *k*. The plug 27 has not yet been removed from the jack 30. It is thus seen that if the mine is not level, the pendulum is tilted and the contact disk 9 is in contact with one or more of the contact points 24 mounted on the contact ring 10. Hence there is a continuous electrical circuit through the battery 19, the voltmeter 23, one side 28 of the plug 27, one prong 26 of the jack 30, and through the pendulum switch. The meter 23 gives a reading showing the above circuit is complete. The mine is then tilted or leveled until the meter reads zero voltage, indicating that the pendulum switch is open. Since the mine is now level, the meter is disconnected and the pull ring 34 pulled so as to pull the plug 27 out of the jack 30, whereupon the contact prongs 25 and 26 spring together into electrical contact with each other. This places the battery 19 in a series circuit with the detonator and the circuit is only open at the pendulum switch since the contact disk 9 is not touching any of the contact points 24. If the mine should now be tilted or moved, the relatively heavy pendulum weight 8 will swing relative to the rest of the mine, and the contact disk 9 will touch one of the contact points 24, closing the series circuit whereupon current will flow from the battery 19 through the electric detonator 20, exploding it and hence setting off the mine.

Thus the device effectively prevents removal of the mine until it is exploded by pressure or other external means. Once the mine has been installed, the wire *k* may be cut close to the aperture 31 and the end pushed back inside the mine so it cannot be reached.

Figure 3 shows a sectional view of a floating marine mine which is designed to explode on contact with a passing ship. To prevent removal of the mine, it is also equipped with the safety device shown. In the drawing a marine mine 35 has a platform or bulkhead 36 dividing its interior into an upper chamber 37 and a lower chamber 38. The outer mine surface of the chamber 38 is punctured with a multitude of holes 54 so as to allow the water to entirely fill the lower chamber 38 when the mine is placed in the water. A hollow tube 40 connects to a central aperture 41 in the platform 36 by means of a funnel shaped portion 39 and leads through two successive U-shaped tube bends 42 and 43

of small cross section, forming a gooseneck as shown, into a small diameter upright tube 43 having at its upper extremity an air chamber 45. The tube bend 43 contains two electric contacts 46 and 47 positioned near each other but not touching, and they are connected to the outside of the tube by wires leading through the tube 40 and insulated thereupon. A quantity of liquid mercury 48 occupies the tube bend 43, its quantity being sufficient to close off the tube comprising the U-shaped portion 43 so as to prevent air from passing through the tube past the mercury.

One contact 46 is connected by wire 49 to one terminal of an electric detonator 20, the other terminal of which is connected by wire 50 to one terminal of an electric battery 19. The other terminal of the battery is connected by wire 51 to the moving contact arms 11, 12 and 13 of a triple combination switch 52, all contact arms being connected together electrically. Each contact arm is adapted to make contact with any one of four contact points, one of which is dead as heretofore explained, and the other three contact points are connected together and denoted live contacts. All three sets 14, 15 and 16 of live contacts are connected together and connected by wire 53 to the contact 47 in the tube bend 43.

When the mine is lowered into the water, it 30 seeps through the holes 54 into the chamber 38, up through the funnel 39 and tube 40 compressing any trapped air in tube bend 42 down into tube bend 43, forcing mercury 48 up into tube 44 and thus breaking the electrical connection between the two contacts 46 and 47. The air in the chamber 45 is compressed by the upward movement of the mercury in the tube 44.

Since the battery, detonator, combination switch and mercury switch are all connected in series, it follows that the three movable arms of the combination switch 52 must be set on dead contacts while the mine is being placed in the water up to the water level 55. When this has been done, the mercury switch is open due to the water pressure as already explained. Then the combination switch 52 is set to live contacts. If the mine should now be lifted out of the water, the water drops out of the chamber 38 and funnel 39. The air pressure in chamber 45 forces the mercury down into the tube bend 43 so that it makes contact between contacts 46 and 47, thereby closing the electrical circuit and causing current to flow through the electric detonator 20 exploding the mine.

While the foregoing specification sets forth the invention in specific terms, it is to be understood that numerous changes in the shape, size, arrangement and materials may be resorted to without departing from the spirit and scope of the invention as claimed hereinafter.

I claim:

10 A land mine having a casing, electrical anti-disturbance means including electrically operable explosive means, a source of electric current associated with said explosive means for igniting same, a circuit including said explosive means, said current source and a normally open inertia-sensitive anti-disturbance switch arranged to close upon substantial physical disturbance of said mine, means external to said mine for indicating the circuit condition of said anti-disturbance switch, additional switch arming means comprising a pair of cooperating switch contact members spring-urged toward each other, an insulated member between said contact members for rendering said anti-disturbance means inoperative to ignite said explosive means whereby said mine may be placed in position in disarmed condition, and a flexible tension member operable from the exterior of said casing for pulling said insulating member from between said contact members to arm but not thereafter to disarm said mine.
